UNITED STATES PATENT OFFICE.

WILLIAM J. HOPPER, OF BRUNSWICK, GEORGIA.

WINDOW-BLIND.

1,242,940.

Specification of Letters Patent. Patented Oct. 16, 1917.

Application filed December 9, 1916. Serial No. 136,032.

To all whom it may concern:

Be it known that I, WILLIAM J. HOPPER, a citizen of the United States, residing at Brunswick, in the county of Glynn and State of Georgia, have invented certain useful Improvements in Window-Blinds, of which the following is a specification, reference being had therein to the accompanying drawing.

10 This invention relates to a window blind, and more particularly to the class of blinds adapted to be applied and removed from a window frame without disturbing the window sashes or the ordinary wire screens usually employed.

One of the objects of the invention is to provide means whereby the blind may be attached to the interior of the window frame so as to preclude the possibility of the interior of the room being viewed by unauthorized persons and without precluding the efficient ventilation through the window.

Another object of the invention is the provision of a blind of this character wherein the construction thereof permits the application of the same to variable sized window casings and can be attached to and removed from the casing with despatch.

Another object of the invention is the provision of a blind of this character which is extremely simple in construction, thoroughly reliable and efficient in its purpose, will cut off the view of the room from the outside without appreciably interfering with the light or illumination of the room, and also one which is inexpensive in manufacture.

With these and other objects in view, the invention consists in the features of construction, combination and arrangement of parts as will be hereinafter fully described, illustrated in the accompanying drawing and pointed out in the claims hereunto appended.

45 In the accompanying drawings:

Figure 1 is a perspective view of a window frame to which the invention is attached;

Fig. 2 is a detail perspective view of the 50 blind removed; and

Fig. 3 is a horizontal or cross sectional view through the window frame and blind.

Similar reference characters indicate corresponding parts throughout the several 55 views.

Referring to the drawings in detail, A

designates a window casing or frame which is of the ordinary well known construction, and to which is adapted to be detachably mounted the blind which may be constructed from any suitable material, but preferably constructed from sheet metal.

The invention herein shown comprises an outwardly bowed portion 1, having the window frame engaging edge portions 2 and 3, respectively, which are resilient relative to the bowed portion 1, each being bent on itself at 4 to provide the reinforcing wings 5 disposed against the inner faces of the edge portions 2 and 3 as shown, and thus afford the reinforced window frame engaging panels.

The window frame engaging portions 2 and 3 in their folded edges 4 are provided with notches 6 for the reception of fastening devices carried by the facing strips 7 of the window frame or casing A, these fastening devices being in the form of eye screws 8, which are engaged in the window frame, as is clearly shown in Fig. 1 of the drawing.

On the outer faces of the panels or window frame engaging edge portions 2 and 3 are vertical rails or cleats 9 and 10 which are adapted to rest against the front face of the strips 7 on the window frame, so that they assist to form a rigid connection with the window frame, and thereby prevent undue rattling or vibration of the blind.

The sheet from which the blind is constructed is provided with a plurality of cuts or slits to form air openings 11, which permit a free circulation of air therethrough, but which do not serve as sight openings, owing to the fact that they are partially closed or shielded by the disposed bent portions 12, which originally filled said air openings and constitute tongues serving as louvers. The slits may be formed with dies or shears and the struck out portions 12 may be bent back any desired distance to suit the fancy of the user of the blind.

The portion 1 of the blind is bowed to afford an artistic appearance, and additionally to provide for a greater ventilating surface while such bowing of the sheet renders the same relatively resilient so that it will snugly fit the window casing or frame A and is adaptable for various sizes thereof as will be obvious. However, it is to be understood that the particular form of blind shown need not be followed in every in-

stance. Mounted in the reinforcing portions 5 at the inner side of the blind are eye members 13, carrying hook catches 14, which are adapted for detachable engagement in the eye screws 8 for the detachable fastening of the blind to the window frame or casing A, as will be apparent.

From the foregoing, it will be apparent that I have provided a simple, durable, and 10 efficient blind which may be readily constructed of sheet metal, and made in a single operation of a stamping and cutting machine by first being die struck to provide cut out portions and then formed into shape, 15 after which the stops or cleats 9 and 10 may be secured.

If desired, handles 15 may be attached to the inner sides of the panels 2 and 3 for the purpose of attaching and removing the 20 blind without undue inconvenience to the user thereof.

What is claimed is:—

1. A window blind including a body formed from a single piece of resilient sheet 25 metal, an intermediate portion of which is bowed, tongues struck out from the intermediate portion and providing air spaces therein, window frame engaging edge portions continuing from the sides of the inter-

mediate portion and having their outer ends 30 folded upon themselves forming reinforcing strips, window frame engaging cleats carried by the outer faces of the edge portions, and means for adjustably fastening the blind to the frame of the window. 35

2. The combination of a window frame and eyes mounted on the inner surface of the sides thereof, of a blind embodying a bowed portion, tongues struck out from the bowed portion and providing air spaces 40 therein, resilient window frame engaging edge portions continuing from the sides of the bowed portion, reinforcing strips formed on the outer ends of the edge portions, window frame engaging cleats secured to the 45 outer surfaces of the edge portions for abutting the sides of the window frame, the edge portions and the reinforcing strips having notches therein adapted for engagement about the eyes when the cleats abut the sides 50 of the frame, handles on the strips for facilitating application of the blinds, and fastening means on the strips for engagement with the eyes for detachably fastening the blind in position. 55

In testimony whereof I affix my signature.

WILLIAM J. HOPPER.
